UNITED STATES PATENT OFFICE.

WILLIAM M. SMITH, OF EVANSVILLE, INDIANA.

AUTOMATIC TRAIN-STOP.

1,133,239.

Specification of Letters Patent. Patented Mar. 23, 1915.

Application filed October 5, 1914. Serial No. 865,092.

To all whom it may concern:

Be it known that I, WILLIAM M. SMITH, a citizen of the United States, residing at Evansville, county of Vanderburgh, and State of Indiana, have invented certain new and useful Improvements in Automatic Train-Stops, of which the following is a specification.

This invention relates to automatic train-stops.

My object is to provide improved automatic mechanism, whereby air brakes of a moving locomotive, car, or train, will be automatically applied if the engineer or motorman passes a signal set against him.

The present invention relates to that class of automatic train stops embodying a trip on the locomotive, car, or train, which is struck by another trip operated in conjunction with a signal or semaphore and cooperates with novel means to automatically throw the engineer's air brake valve to the emergency position by the utilization of compressed air operated means operating in conjunction with the trip.

The present invention consists in those improvements and novel combinations of parts and mechanisms which are hereinafter set forth.

In the accompanying drawings: Figure 1 is a view of the complete invention; Fig. 2, a partly sectional, partly full-line view of the train-carried trip; Fig. 3, a detail plan of the operating device which is applied to the engineer's brake valve; Fig. 4, an elevation, partly in section, of the plunger, valve operated thereby, and latching devices; Fig. 5, a horizontal section through the operating device for the engineer's brake valve; and Fig. 6, a detail, partly in section, of the cushioning device for the train-carried trip.

I have illustrated my invention as applied to the cab of a locomotive, but it is as well adapted for use in connection with a motor-driven car or other vehicle employing air brakes.

On opposite sides of the cab 1 are trip mechanisms 2, either or both of which may be adapted for use. These trip mechanisms being duplicates, a description of one will suffice. A shell or casing 3 is suitably secured by fastenings 4 to the cab 1. Hinged to the shell or casing 3 at 5 is a lid or cover 6 for the casing 3. Secured rigidly to the lid or cover and rising therefrom is an arm

7. A trip 8 is hinged at 9 to the arm 7 and has connected thereto an arm 10 to which is connected a plunger or piston 11 operating against a spring 12 in a dash-pot 13. The spring 12, arm 10 and plunger 11 constitute means for holding the trip 8 normally extended and forming a continuation of the arm 7 and constituting a cushion to properly resist the forward movement of the trip 8 when the car or locomotive is backed out of the block after it has struck the semaphore trip, as subsequently described, without causing injury to said trip 8. The hinge 9 is so arranged that when the trip 8 is struck by the semaphore trip arm, as when the locomotive runs by a signal set against it, the arm 7 and trip 8 are in effect a single rigid arm adapted to move with the head 6 on the hinge 5. This movement is resisted and cushioned by a spring 14 surrounding a rod 15 which is connected at 16 to the head 6 and at its lower end is connected at 17 to the operating link 18 which releases the latch 19.

The latch 19 is pivoted at 20 to a guide or standard 21 and is normally pressed by spring 22 into engagement with the head 23 of the operating plunger 24 which is slidable in the casing 25 and is carried by a plate 26 which may be suitably secured to the cab. A spring 27 tends to press the operating plunger 24 outwardly in relation to its casing 25, but this movement is prevented by the latching parts 19 and 23. To re-set the plunger 24 and latch 23, after they have operated, I provide a hand lever 28 which is pivoted at 29 and is provided with a fork 30 which is adapted to engage pins 31 on the plunger 24 and which operate in slots 32 and prevent the plunger 24 from turning, thereby insuring the proper position of the latch 23 so that it may be engaged by the latch 19 when the former is raised.

The mechanism just described is positioned adjacent a spring-seated valve 33 and, preferably, the casing 25 is connected to the valve casing by a suitable yoke 34 to insure the plunger 24 being in alinement with the stem 35 of the valve 33. When the plunger 24 is in its raised or latched position, it is just above the upper end of the stem 35 and the valve 33 is then closed. The valve 33 controls an air pipe line 36 and by the admission and cut off of the air pressure, operates the mechanism which turns the engineer's air brake valve.

The invention is adapted for application to the ordinary engineer's brake valve having the casing 37 and handle 38 and as this construction is well known, further description is unnecessary.

My improved mechanism for shifting the handle 38 is carried by a yoke 39 which has screws 40 adapted to engage the sides of the casing 37 to secure the frame in proper relation thereto. To the frame 39 is suitably fastened as at 41, a casting 42 in which is mounted a short shaft 43 which carries on its upper end a pinion 44 and on its lower end an operating arm 45, the latter projecting downwardly so that it is adapted to bear against the handle 38 of the brake valve. Secured to the frame 42 is a cylinder 46 in which operates a spring-retracted piston 47 to whose piston rod is connected a rack 48 which meshes with the pinion 44. Normally the spring holds the piston 47 in retracted position and the operating arm 45 is then retracted to such point that it will not interfere with the free manipulation of the handle 38 by the engineer or motorman so that the air brake valve may be used in the ordinary manner for applying or letting off the air brakes. When, however, air is admitted through pipe 36 by the opening 58 of the valve 33 by descent of plunger 24, the air pressure admitted to the cylinder advances the piston 47 against the action of its spring and turns the pinion 44, instantly throwing the handle 38 to the emergency position and applying the air brakes. After the mechanism has acted, the handle 38 is operated to restore the plunger 24 to normal position and cause re-latching of the parts 19 and 23, whereupon the valve 33 40 re-seats itself and cuts off the admission of air back of piston 47, but there is a residual air pressure in the cylinder pipe 36 and I, therefore, provide a hand-operated bleed valve 49 which can be opened to let out this air, whereupon the spring causes the operating arm 45 to be retracted and the handle 38 can then be brought back to running position by hand.

As thus far described, my invention constitutes a complete and operative mechanism, as it is obvious that the trip 8 can be operated by any means desired. I prefer, however, to provide an operating trip 50 which is journaled at 51 to an arm 52 extending out from the semaphore tower or stand 53, and to operatively connect this trip 50 to the semaphore arm 54 by a sprocket chain 55 running over gears carried by the arm 50 and the semaphore arm 54 and to 60 arrange the parts so that when the semaphore is set for "clear" the trip 50 will likewise be arranged vertically, and when the semaphore is set at "stop," the trip 50 will be arranged horizontally, or substantially 65 so, in position to be struck by the trip 8.

The trip 50 may be provided with a counterbalanced weight 56.

If a "clear" signal is displayed, the trip 8 will not be struck and consequently, the handle 38 will not be operated automatically and will still be subject to hand operation. If, however, the semaphore 54 is set at "danger" or "stop," the trip 50 will be set by the movement of the semaphore and will then be arranged in the path of travel 70 of the trip 8. Immediately the trip 8 strikes the trip 50, the trip 8 and arm 7 will move as an entirety on the pivot 5 and against the restoring action of the spring 14. The latch 19 will then be released from the latch head 80 23 and the spring 27 will thereupon immediately snap the plunger 24 downwardly. As the spring 27 is stronger than the spring of valve 33, the valve 33 will be opened and held in open position. Air pressure through 85 pipe 36 then operates the plunger 47, which through the rack 48 and pinion 44, instantly swings the arm 45 and the latter throws the handle 38 to the emergency position. Consequently, if the engineer or motorman has 90 not observed the signal which is set against him, the brakes will be automatically applied.

Having thus described my invention, what I claim as new and desire to secure by Letters Patent, is:

1. In an automatic train stop, a trip adapted to be carried by the movable car, said trip being composed of parts jointed together and adapted to move as an entirety in one direction and to move in relation to each other, spring means coöoperating with the complete trip to cushion the movement thereof when it moves as an entirety, and spring means coöperating with the movable section of the trip.

2. In an automatic train stop, the combination with an air-brake valve, of self-contained supplemental operating means therefor comprising a frame having means 110 for its connection to the casing of the air-brake valve, a swinging operating arm carried by said frame and loosely associated with the air-brake valve and normally arranged so that the air-brake valve may be 115 manipulated without interference thereby, air operated means on the frame adapted for shifting the arm, and trip operated means for controlling said arm-operating means.

3. In an automatic train stop, the combination with an air-brake valve, of self-contained supplemental operating means therefor comprising a frame having means 125 for its connection to the casing of the air-brake valve, a swinging operating arm carried by said frame and loosely associated with the air-brake valve and normally arranged so that the air-brake valve may be 130 manipulated without interference thereby,

a cylinder on the frame, a spring retracted piston operating therein, an operative connection between the piston and the arm, and trip operated means for controlling the operation of said cylinder.

4. In an automatic trainstop, the combination with an air-brake valve, of self-contained supplemental operating means therefor comprising a frame having means for its connection to the casing of the air-brake valve, a swinging operating arm carried by said frame and loosely associated with the air brake valve and normally arranged so that the air brake valve may be manipulated without interference thereby, a cylinder on the frame, a spring-retracted piston operating therein, an operative con-

nection between the piston and the arm, means for supplying air to the cylinder embodying a normally spring-seated valve, and trip operated mechanism comprising a spring-actuated plunger adapted to engage and open said valve when said plunger is released, a latch for normally holding said plunger retracted, a trip cooperatively related to the latch, and means for restoring the operating plunger to latched position. 20 25

In testimony whereof, I hereunto affix my signature in presence of two witnesses.

WILLIAM M. SMITH.
